UNITED STATES PATENT OFFICE.

FRANCIS L. FREAS, OF CONSHOHOCKEN, PENNSYLVANIA.

HYDROMETER-SYRINGE.

1,262,478.

Specification of Letters Patent. Patented Apr. 9, 1918.

Application filed October 15, 1917. Serial No. 196,581.

To all whom it may concern:

Be it known that I, FRANCIS L. FREAS, a citizen of the United States, residing in Conshohocken, in the county of Montgomery and State of Pennsylvania, have invented 5 certain new and useful Improvements in Hydrometer-Syringes, whereof the following is a specification, reference being had to the accompanying drawings.

10 My invention relates to a so-called hydrometer syringe which is employed, for instance, in testing storage batteries, or for other similar uses, and the improvements are addressed toward protecting the fragile 15 hydrometer element of the syringe, and also the glass casing, from accidental injury in case the device should be dropped, or laid down too forcibly under ordinary conditions of use.

20 Figure I, represents an external side elevation of the device in its preferred form.

Fig. II, is a longitudinal axial section thereof.

25 Fig. III, is a side elevation of the hydrometer element.

The device, in the embodiment shown, consists of a cylindrical main float chamber 1, which is made of glass, or other transparent material. Said chamber is tapered to a 30 reduced diameter at one end and the extremity of the orifice is provided with a circumferential flange 2, so as to receive, and form a close joint, with a hollow rubber compression bulb 3. A soft rubber tubular 35 buffer 4, is tightly inserted in the orifice, and projects inwardly a short distance clear of the tapered wall, as shown in Fig. II.

The other end portion of the chamber 1, is preferably slightly reduced, while remaining cylindrical, as shown, and is externally threaded so as to engage in a correspondingly threaded portion 6, of an extension piece 7, which is preferably made of rubber having a moderate degree of pliability.

45 Said piece 7, constitutes an extension chamber, preferably of considerable axial length, as indicated, and is provided, at a substantial distance from the portion 6, with a disk-shaped end wall having a flange 10, of deep

50 radial extent, beyond which wall it is further provided with an axial elongated nozzle piece 8, of reduced diameter, and, therefore, relatively more flexible as a whole than the main body 7, of the extension piece.

55 A diametrical trough or groove 11, is formed across the inner face of the end wall, to

afford a free passage for liquid when the hydrometer element is resting upon the wall.

By reference to the drawings it will be noted that although what may be called the 60 rear end portion 6, of the extension chamber 7, may be conveniently somewhat enlarged to afford a proper seat for the screw thread which engages the end of the chamber 1, this enlargement is substantially less 65 in external radial projection than the flange 10, and also than the maximum radial projection of the bulb 3. Furthermore, it will be noted that the cylindrical wall of the extension chamber beyond the portion 6, is 70 of less internal diameter than the proximate end of the main chamber.

The hydrometer element proper is represented in Fig. III, and is of the well-known type comprising a graduated stem 12, and 75 an elongated bulb 13, the latter being pivotally weighted with shot 14, or in any convenient manner. The dimensions of the hydrometer element are definitely related to those of the float chamber and extension. 80 Thus, the diameter of the bulb portion 13, is such that while it can move freely within the extension chamber 7, it cannot, when contained therein for a substantial portion of its length, tilt sufficiently for the stem 12, 85 to come into contact with the wall of the main float chamber 1.

The length of the hydrometer is such that when in its extreme position of withdrawal from the extension chamber (as indicated 90 in dotted lines), the end of the stem 12, will come into contact with the buffer piece 4, while the bulb is still sufficiently within the extension chamber, to come into contact with the rubber surface thereof, instead of 95 striking the surface of the glass float chamber 1. Furthermore, the diameter of the stem is less than that of the orifice at the region of the buffer 4, so that the stem cannot slip into the bulb 3, and be broken when 100 the latter is compressed, as frequently happens in previous devices of this general character.

If the device, containing the hydrometer element, should be dropped accidentally, or 105 laid down too forcibly, the direct shock will be borne by the elastic bulb 3, and the flange 10, neither the portion 6, (which surrounds and is in direct contact with the extremity of the main chamber 1) nor the side wall 110 of the extension chamber 7, making any direct contact with the external surface.

Furthermore, it will be seen that by reason of the substantial axial length of the extension chamber and the distinct, though slight flexibility thereof in an axial direction, the 5 transmitted shock will be minimized and the danger of breakage will be much less than if the part of the extension chamber which is in direct contact with the glass casing, as at 6, were relied on as the projecting guard 10 portion.

Having thus described my invention, I claim:

1. The combination, with the compression bulb, and the main float chamber; of a 15 relatively flexible extension chamber having one extremity adapted to engage the float chamber and provided at the other extremity with a wall of substantially greater radial depth than any portion of the device 20 intervening between the region of maximum diameter of the compression bulb and said flange; said extension chamber being also

provided with a reduced nozzle piece, substantially as set forth.

2. The combination, of the compression 25 bulb; the main float chamber having a reduced orifice provided with a tubular buffer piece; the rubber extension chamber of less internal diameter than the main chamber, and having an end wall provided with a 30 deep radial flange; and the hydrometer element comprising an elongated bulb and a stem, the total length of said element being greater than the distance between the buffer piece and the other end of the main chamber, 35 substantially as set forth.

In testimony whereof, I have hereunto signed my name at Philadelphia, Pennsylvania, this twelfth day of October, 1917.

FRANCIS L. FREAS.
